ABRASIVE BELT

Eric P. Dahlstrom, Niagara Falls, N. Y., assignor
to The Carborundum Company, Niagara Falls,
N. Y., a corporation of Delaware

Application December 9, 1938, Serial No. 244,795

1 Claim. (Cl. 51—188)

This invention relates to abrasive belts and to the method of making the same. More particularly, it relates to joints or splices in abrasive belts and to the method of making said joints or splices.

One object of the invention is to provide abrasive belts having improved joints or splices. Another object is to provide a method of making improved joints or splices in abrasive belts. Other objects will become apparent from the following disclosure.

In order that a full understanding of the invention may be had, reference is made to the appended drawing, in which

15 Figure 1 is a plan view of a portion of coated abrasive material designed for use in one modification of the present invention;

20 Figure 2 is a plan view of a portion of abrasive coated material adapted to adjoin the portion illustrated in Figure 1;

Figure 3 is a plan view of a portion of a belt embodying one modification of the present invention, in which the portions separately illustrated in Figures 1 and 2 are shown joined;

25 Figure 4 is an enlarged cross-sectional view, along the line IV—IV of Figure 3, of a portion of a belt embodying the modification illustrated in Figure 3 after the sections shown in Figures 1 and 2 have been placed in juxtaposition but 30 before the two sections have been compressed firmly together to form a close strong joint;

Figure 5 is a plan view of a portion of a belt embodying another modification of the present invention;

35 Figure 6 is a plan view of a portion of a belt embodying still another modification of the present invention; and

Figure 7 is a plan view of a portion of a belt embodying still another modification of the present invention.

In making a belt according to the modification of the present invention illustrated in Figures 1, 2, 3 and 4, a piece of abrasive coated flexible material 1 of suitable size is prepared for the joining operation by forming a salient edge 2 on one end of the piece and removing the abrasive coating in the vicinity 3 of the salient edge. As illustrated, the abrasive-free area 3 is bounded by the edge 2 of the salient on one side and by the edge 4 of the abrasive coating, which is of substantially the same contour as the edge of the salient. The contour of the edge of the salient illustrated in Figures 1, 3 and 4 is formed 55 by the intersection, at the center line of the belt,

of two straight lines 5 and 6, which are of the same length.

The portion 10 of abrasive coated flexible material to be joined to the salient portion described above is illustrated in Figure 2, and, as shown 5 there, is formed with a boundary 11 that is re-entrant and complementary to the salient edge 2 described above. In this piece, the abrasive grain coating extends to the edge or boundary 11 of the reentrant edge.

10 The abrasive-free area 3 of the salient 2 may be formed in various ways, but it has been found to be convenient to remove the abrasive grains from a fully coated sheet, that is, a sheet in which the abrasive grain coating extends from 15 edge to edge, by the careful application of a rotating abrasive wheel to the part of the sheet that is to be freed of abrasive grains.

Careful application of a rotating abrasive wheel to the abrasive coated sheet will remove 20 the abrasive grains and most or substantially all of the adhesive without damaging the flexible backing material.

The abrasive-free area 3 at the salient edge 25 of the piece 1 having been provided, the uncoated area 3 is coated with adhesive of the desired character and the piece 10 with the reentrant and complementary edge is placed on top of the abrasive-free and adhesive coated portion 3 so that the abrasive boundary 4 of the salient piece 30 1 and the boundary 11 of the reentrant piece 10 are in register and so that the edges 20 and 21 line up in a straight line on one side and the edges 22 and 23 line up in a straight line on the other side, as illustrated in Figure 3. The overlapped portions of the two pieces are then pressed 35 together and held so that they cannot move while the adhesive is setting.

Figure 4 shows in elevation an enlarged view 40 of a section along the line IV—IV of the joint shown in Figure 3. In Figure 4 the backing 30 of the piece 10 is shown to be in intimate contact with the backing 31 of the piece 1. These backings may be of any suitable flexible material, such as paper, cloth, fibre, metal or other flexible 45 sheet material or of any suitable combination of two or more of such materials in laminated form. In Figure 4 the joint is shown after the two end portions of the belt have been placed in juxtaposition but before the final pressure is put on 50 them to force them into more intimate relationship and compress the layers closer together.

Figure 5 shows a plan view of a modified belt joint made according to the present invention, where the salient end portion is angular, but the 55

5 apex of the salient angle is not located at the exact center line of the belt but is positioned somewhat to one side of the center line. This off-center location of the apex of the salient portion is found to be advantageous in correcting the tracking of the belt in some cases where the tracking cannot be corrected by adjustment of the crown pulleys, and sometimes serves to deter the belt from a tendency to track sideways off 10 the pulleys.

10 Figure 6 shows a plan view of a further modification of the present invention where the apex of the salient portion of the belt end is not sharp and angular but where the apex portion has been 15 rounded off to remove the angular intersection portion of the salient. This shape can be used to advantage where the belt formed passes over certain types of pulley shapes.

20 Figure 7 shows a plan view of a still further modification of the present invention where the salient end portion of the belt is in the shape of a semicircle. In this modification a straight line cannot be drawn which will fall on the line of 25 junction of the belt ends, but will always merely cross the joint, since the direction of the joint is constantly changing. This effect is obtained while still retaining all the advantages of a salient joint and the construction of the present invention.

30 The joints shown in Figures 5, 6 and 7 are all likewise formed in the manner set forth in connection with the belt portions shown in Figures 1 to 4.

35 Belts possessing joints or splices made according to the present invention possess numerous advantages over belts jointed by the methods heretofore used. Heretofore belt joints have either been made so that the line of joining between two adjacent belt ends laid either perpendicular to the line of movement of the belt or in a single direction oblique thereto. Slight variations in 40 this procedure have been to give such joints an irregularity by curving or otherwise zig-zagging or serrating the line of joining in order to strengthen the joint. However, by the present 45 invention of a joint wherein the end of one belt section has a contour such that the central portion of the end boundary is protruding or salient 50 with respect to the portions of the end boundary at either side thereto, and the second or adjoining section has a complementary re-entrant shaped end, a belt is obtained of improved running characteristics. By the use of such belt joints 55 the belt is given what might be termed an automatic oscillating effect. As the belt joint of the present invention passes over the crown pulley there is a tendency to draw toward the center. Then as the splice or joint leaves the crown, 60 it may tend to track one way or another, depending upon the alignment of the remaining pulleys; but as the splice again goes over the crown, it again tends to center itself. This effect is of 65 particular value in the use of wide belts. Minor tendencies to track to one side or the other can often be counteracted by proper alignment of the pulleys but in cases where it is impossible to obtain suitable adjustment of the pulleys to cause 70 the belt to track satisfactorily it is found that the belt splice of the present invention serves to give a centering of the belt by the above-explained

automatic oscillating action in a highly satisfactory way.

Furthermore, by still retaining an oblique direction of the joint with respect to the movement of the belt the belt is caused to run smoothly and 5 with little or no vibration since the joint is gradually presented under the work instead of suddenly appearing.

6 A further decided advantage of the present invention is its simplicity of construction of the belt 10 joint or splices. Previous efforts to obtain a belt having similar operating advantages have led to the use of complicated joint structures involving cumbersome and time-wasting methods of jointure. Resort has been had to constructions 15 whereby the end portion need be slotted for insertion of the abutting end section, or tongue or tab arrangements have been used, which tabs or tongues have to be interlocked or fitted together. The present invention avoids these manufacturing 20 disadvantages in a very simple but ingenious way by forming the two end sections into a salient and a corresponding complementary re-entrant shaped end section, skiving the abrasive from the 25 end edge portion of the salient section and joining the two in the manner previously described in detail. The salient section is much easier to clear of abrasive from the portion bordering the end without injury to the adjacent abrasive areas 30 than is removal of abrasive from the re-entrant portion. Therefore in the making of belts there is a decided saving of time and a lower number of rejections of belts due to defects in the joint.

35 A further advantage of the belt joint of the present invention resides in the fact that when in operating the belt is run in a direction so that the joint approaches the work with the apex foremost, in other words, the belts as illustrated in the accompanying figures would move in operation from left to right, the belt in passing under the work proceeds from a higher to a lower level at all points along the joint. This prevents any catching of the joint on the work with subsequent 40 destruction of the belt.

45 It is to be understood that while this invention has been described in connection with belts formed from a single abrasive strip with the ends joined, it is particularly well adapted to forming extra wide belts from a number of pieces of 50 abrasive material where the width of the belt is greater than the width of the original abrasive strips, thus necessitating the use of numerous pieces of abrasive sheet material joined in several places.

55 Other advantages are readily discernible upon consideration of the invention herein set forth. Having described my invention in its preferred embodiment I do not wish to limit myself other 60 than by the scope of the appended claim.

65 I claim:

In an abrasive belt, a joint between adjoining portions which comprises a plurality of layers in juxtaposition and adhesively united, the under layer being bounded at the juncture by a salient edge and being free of abrasive material in the area bounded by said salient edge and a line of substantially the same contour but spaced apart therefrom, the upper layer being bounded at the 70 juncture by an edge which is re-entrant and complementary to the salient edge of the lower layer.

ERIC P. DAHLSTROM.
